SPIKE AND NAIL EXTRACTOR

Filed Nov. 6, 1931

UNITED STATES PATENT OFFICE

FRED SWOYER, OF SILVER GROVE, KENTUCKY

SPIKE AND NAIL EXTRACTOR

Application filed November 6, 1931. Serial No. 573,460.

This invention relates to a nail and spike extractor.

One object of the present invention is to improve the construction of nail and spike extractors and to provide a simple, practical and efficient nail and spike extractor of strong, durable and comparatively inexpensive construction, equipped with a plurality of nail and spike extracting jaws adapted to successively operate on a nail or spike and coact with a single fulcrum of the extractor and obviate the necessity of employing a so-called heel or other means supplemental to a single fulcrum face for enabling the final stages of the extraction of a long nail or spike to be completed.

Another object of the invention resides in the provision of a nail and spike extractor equipped with a relatively short outer claw adapted to enable great leverage to be exerted on a nail or spike to start it so that the nail or spike, after being started, may be successively operated on by a relatively long claw to completely extract the nail or spike, the structure being such as to admit of full and unobstructed view of the outer claw when engaging it with a nail or like fastening to be extracted.

Another object of the invention is to provide a device of the nature stated embodying the relatively short and relatively long outer and inner claws so as to coact with a single fulcrum to obviate the necessity of providing a plurality of fulcrums and of changing the fulcrum in changing from one claw to another.

It is still further designed to provide an implement of the nature stated, embodying among other characteristics, two separate claws, one disposed above the other, the structure being such as to admit a full and unobstructed view of the lowermost claw when engaging it with a nail or like fastening to be extracted.

With these and other objects in view, the invention consists in the construction and novel combination and arrangement of parts hereinafter described, illustrated in the accompanying drawing, and set forth in the claims hereto appended, it being understood

that various changes in the form, proportion, and minor details of construction, within the scope of the claims, may be resorted to without departing from the spirit of the invention or sacrificing any of the advantages thereof.

In the drawing:—

Figure 1 is a perspective view of a nail and spike extracting implement embodying the invention, an intermediate portion of the bar or handle being broken away.

Fig. 2 is a front view, the bar being broken away.

Fig. 3 is a sectional view on the line 3—3 of Fig. 2, looking in the direction of the arrows.

Fig. 4 is a sectional view on the line 4—4 of Fig. 3.

Referring now more particularly to the accompanying drawing, in which is illustrated the preferred form of the present invention, the device comprises in its construction a bar or shank 1 consisting of a substantially straight bar which may be of any desired form in cross section and having its outer end enlarged for strength as at 2 and curved to form a rolling fulcrum 3, the enlargement being directed laterally from the lower end of the bar or shank 1, as shown. This enlarged portion 2 is hollowed out to provide an opening 4 through which the outer claw 5, located at the bottom of the opening, can be readily seen by the operator in his attempt to engage the outer claw with a nail, spike or the like. Side walls 6 and 7 result from the hollow enlargement which are effectively braced by reason of the rear wall 8 and the connection between the outer end of the side wall and the inner claw 9 which latter is arranged above the outer claw 5 and which projects beyond the outer claw, as clearly shown in the drawing.

The hollowed out portion which forms the opening 4 provides a nail or spike head receiving pocket which is open at the top and at the front and closed at the sides and back and substantially at the bottom as the outer claw 5 is located at the bottom of the pocket or opening and extends longitudinally thereof from the front of the same to the rear

wall thereof. The sides or members of the claw project inwardly from the side walls 6 and 7 and are beveled laterally and having converging longitudinal edges which form 5 a tapering space between the sides or members of the lower or outer claw. The lower faces of the sides or members of the lower or outer claw merge into the face of the rolling fulcrum 3, as clearly illustrated in Fig. 10 3 of the drawing.

The space formed between the side walls 6 and 7 by reason of the hollow form of enlargement constitutes an opening which admits of unobstructed view of the outer claw 15 5 when the adjusting the same to the head of a nail, spike or like fastening. Both claws 5 and 9 project outwardly from the bar 1 at approximately a right angle thereto with the result that a maximum leverage is afforded 20 for extracting the fastening to be withdrawn and the rolling fulcrum 3 being common to both claws, constitutes a part common to the bar 1 and side walls 6 and 7.

The upper or inner claw which projects 25 forwardly from the pocket or opening 4 at the top thereof extends upwardly and outwardly and is arranged at an acute angle to the lower or inner jaw, as clearly shown in Fig. 3 of the drawing. This will increase the 30 lifting effect of the nail extractor and enable the same to draw a longer nail or spike without bending the same as would be the case where the outer or upper claw disposed in true parallelism with the plane of the lower 35 or inner claw. The inner lower claw is beveled laterally at the upper faces of its sides and the inner side edges of the sides of the upper claw are laterally beveled downwardly and outwardly from the upper faces of 40 the sides of the claw, as clearly illustrated in Fig. 2 of the drawing. The beveling at the upper faces of the sides of the lower inner claw facilitates engagement of the said claw with the head of a nail or spike preparatory 45 to extracting the same and the downward bevel of the upper outer claw enables the same to engage the head of the spike or nail with the upper faces of the side portions of the outer upper claw and, at the same time, 50 provides a clearance space below the engaged upper surfaces for cleaning the shank of the nail or spike and thereby facilitate the extraction of the same without bending the said nail or spike.

55 The hollow space 10 is opened forwardly of the device under the inner claw 9 to permit ready engagement of the outer claw 5 with a nail, spike or the like and in operating the extractor, the relatively short outer claw is 60 first engaged with a nail or spike. This outer jaw having a short leverage enables the operator with a short arm movement to start the extraction of the nail or spike with less effort than with an ordinary single claw, 65 spike and nail extractor which of necessity

and for practicability, must be constructed with a longer leverage than the short outer claw in order to enable the operator of such single claw extractor to complete the extraction of short nails, and spikes, and also to 70 make as full and as complete an extraction of long nails and spikes as possible. After the initial and partial extraction of a nail or spike, the nail is loosened in the hole and can then be further extracted with less effort 75 than at the beginning of the operation. The operator engages the head of the partially extracted nail or spike with the inner relatively long claw, and this claw, having a longer leverage than the outer claw, enables the 80 operator to complete the removal of the nail or spike with another short arm movement and without building up a fulcrum under the single rolling fulcrum formed by the curved end of the shank.

The nail and spike extractor may be constructed of any suitable size and the size of the devices will correspond to the character 85 of the nails or spikes to be extracted.

A much lighter and shorter handle may 90 be employed than is usually required by the ordinary single claw extractor as the relatively short lower or inner claw will enable a nail or spike to be readily started with a short arm movement and the initial stage of 95 the extraction of a heavy nail or spike may be accomplished with much less effort than is required by the ordinary single claw extractor owing to the relatively short outer or lower claw and the relatively great length of 100 the handle. The relatively short outer or lower claw of the nail extractor during the 105 final stages of the extraction of a long nail or spike will come in contact with the nail or spike and thereby eliminate some of the angular pull of the relatively long claw and will materially assist in the ease of the extraction and also in avoiding or preventing bending of a long nail or spike.

What is claimed is:

1. An implement of the character specified comprising a bar having an end portion curved laterally to provide a rolling fulcrum, spaced side walls adjacent the fulcrum end of the bar, an inner claw connecting the outer ends of the side walls, and an outer claw in line with the outer edges of the side walls and the face of the rolling fulcrum.

2. A nail and spike extractor comprising a bar having its outer end extended forwardly and provided with a nail and a spike head receiving pocket having side and rear walls, a lower outer claw constituting the bottom of the pocket and an upper inner claw extending from the outer end of the bar at the top of the pocket and connecting the side walls thereof, said pocket being open at the top and in rear of the inner claw and open 130

at the front between the claws to afford an unobstructed view of the lower outer claw.

3. A nail and spike extractor comprising a bar having its outer end curved forwardly 5 and presenting an outer curved end face forming a single convex rolling fulcrum, said outer end being enlarged and provided with a nail and spike head receiving pocket open at the top and at the front and provided 10 at the bottom with a lower outer claw extending longitudinally of the pocket and formed integral with the side walls of the pocket, and an inner upper claw extending from the outer end of the bar at the top of 15 the said pocket and connecting the side walls thereof.

4. A nail and spike extractor comprising a bar having its outer end curved forwardly and presenting an outer curved end face 20 forming a single convex rolling fulcrum, said outer end being enlarged and provided with a nail and spike head receiving pocket open at the top and at the front and provided at the bottom with a lower outer claw extending 25 longitudinally of the pocket and formed integral with the side walls of the pocket, and an inner upper claw extending from the outer end of the bar at the top of the said pocket and connecting the side walls thereof, said 30 inner upper claw being arranged at an acute angle to the lower claw and the latter having its lower surface merging into the surface of the rolling convex fulcrum.

5. A nail and spike extractor comprising 35 a bar having its outer end extended forwardly and provided with a nail and a spike head receiving pocket having side and rear walls, a lower outer claw constituting the bottom of the pocket and an upper inner claw extending 40 from the outer end of the bar at the top of the pocket and connecting the side walls thereof, said pocket being open at the top and in rear of the inner claw and open at the front between the claws to afford an 45 unobstructed view of the lower outer claw, the inner side edges of the inner claw having a slight lateral bevel downwardly and outwardly and the sides of the lower outer claw being laterally beveled at their upper faces.

50 6. A nail extractor comprising a bar having one end enlarged and directed laterally and having the lower face of the laterally directed enlargement rounded to provide a rolling fulcrum, said enlargement having 55 inner and outer claws extending in the same direction, the inner claw extending forwardly beyond the outer claw, the enlargement having an opening formed therein to form a pocket which opens through the top and 60 also through the front of the enlargement between the claws whereby to admit of an unobstructed view of the outer claw when engaging the same with a nail or like element to be extracted.

65 7. A nail extractor comprising a bar hav-

ing one end enlarged and directed laterally, the lower face of the laterally directed enlargement being round to provide a rolling fulcrum, said enlargement having inner and outer jaws arranged one above the other with the inner or upper claw extending forwardly beyond the lower or outer claw, the enlargement having an opening formed therein to form a pocket which opens through the top of the enlargement in rear of the inner or upper claw and which also opens outwardly through the front of the enlargement between said claws whereby to admit of an unobstructed view of the outer or lower claw when engaging the same with a nail or like element to be extracted.

In testimony whereof I have hereunto set my hand.

FRED SWOYER.
